UNITED STATES PATENT OFFICE.

JOSEPH F. BRIGHTMAN, OF SYRACUSE, NEW YORK.

STEAM-TRAP.

1,327,939.

Specification of Letters Patent.

Patented Jan. 13, 1920.

Application filed April 6, 1917. Serial No. 160,165.

To all whom it may concern:

Be it known that I, JOSEPH F. BRIGHTMAN, a citizen of the United States, and a resident of Syracuse, in the county of Onondaga and State of New York, have invented a certain new and useful Steam-Trap, of which the following is a specification.

This invention has for its object a steam trap which is particularly simple in construction and highly efficient and durable in use in which the container for the water of condensation is stationary; and the invention consists in the combinations and constructions hereinafter set forth and claimed.

In describing this invention reference is had to the accompanying drawings in which like characters designate corresponding parts in all the views.

Figure 1 is a vertical sectional view through the container.

Fig. 2 is a fragmentary sectional view taken on the plane at a right angle to Fig. 1.

Fig. 3 is a sectional view taken on line 3—3, Fig. 1.

Fig. 4 is a diagrammatic view illustrating the steam trap as connected in a heating system.

This steam trap comprises generally, a stationary container having an inlet and an outlet, valves for controlling the inlet and the outlet, and means in the container for controlling the operation of the valves.

1. designates the container which includes a body open at its top and a cap 2 secured to the body in any suitable manner as by bolts 3 extending through annular flanges on the body and the cap 2.

4 and 5 designate respectively, the inlet and the outlet for the container, the inlet 40 being located in the cap 2 and the outlet in the bottom of the container, the inlet and outlet 4, 5 being preferably arranged in alignment.

6 and 7 are valves for controlling the inlet 4 and outlet 5 respectively, these valves being carried by cages 8, 9 threading into the inlet 4 and outlet 5 respectively, and formed with guides 10, 11 in which the stems 12, 13 of the valves slide.

14 and 15 are springs located in the inlet 4 and the outlet 5 respectively, and arranged to normally hold the valves 6 and 7 against the seats on the cages 8, 9.

The container is also formed with a pressure equalizing passage 16, normally closed by a valve 17 carried by the cage 18 and

having a stem 19 in the cage, the valve being held in its closed position by a spring 20 encircling the stem and abutting against the guide 18^a and the shoulder 21 on the 60 stem.

The means for controlling the operation of the valve operates to open the outlet valve 7 and the equalizing valve 17 which are normally in their closed position alternately 65 with the inlet valve 6 which is normally in its open position, said mechanism including gradually movable parts and connections operated by said parts to have a quick action after the gradually moving parts have been 70 actuated a predetermined amount. The gradually movable parts include a float 22 and connections operated by the float. These connections comprise a lever 23 pivoted at 75 24 between its ends to a bracket 25 depending from the cap 2, a rod 26 arranged in axial alinement with the stems 12, 13 of the valves 6, 7; a toggle, one link of which is connected to the rod, the other link of which is connected to the lever and spring normally 80 tending to break the toggle and resist the movement thereof which carries the toggle joint forward and into the dead center line of the toggle. The rod 26 is guided in suitable arms 27 carried by the bracket 25. The 85 toggle is here shown as double in construction and includes a double link 28 pivoted at 29 to a block 30 on the upper end of the rod 26, a double link 31 pivoted at 32 to the link 28 and a link 33 pivoted to the link 31 90 at 34 and to one arm of the lever 23, the other arm of which carries the float 22.

Said connections further include springs 35 connecting the links 28, 31 of the toggle, these springs 35 being connected to the outer 95 ends of the toggle links and normally tending to hold the toggle out of its dead center line, that is, a line passing through the points 34, 32, 36.

The equalizing part is operated by the rod 100 26 through a lever 37 pivoted between its ends at 38 to a bracket 39, one arm of the lever having an adjusting screw 40 coacting with the end of the stem 19 of the valve 17 and the other arm thereof being pivoted at 105 41 to a collar 42 fixed to the rod 26.

In operation, the inlet 4 is connected to a pipe 43 which is the return pipe of a heating system including units as radiators 44 and the outlet 5 is connected by a pipe 45 110 to the boiler 46.

The equalizing passage 16 is connected by

a pipe 47 to the upper part or steam dome of the boiler.

In operation, the outlet valve 9 and the equalizing valve 17 are closed while the valve 5 6 is open. Water of condensation or steam flows into the container, the steam condensing therein, and as the level of the water rises in the container, the float 22 is carried upwardly gradually moving the lever 23, 10 link 23, toggle links 28 and 31 gradually tensioning the springs 35 as they pass into the dead center line from the upper side thereof, and as the joint 32 of the toggle passes to the opposite side of the dead center line from 15 that seen in Fig. 1, the springs complete the opening of the toggle with a quick action forcing the rod 26 downwardly so that the spring 14 will close the intake valve 6 and open the outlet valve 7 against the action of 20 its spring.

This movement also moves the lever 37 to open the equalizing valve 17 so that the pressure within the trap is the same as that in the boiler hence permitting the water to 25 flow into the boiler through the outlet 5 and pipe 43.

As the float falls due to the lowering of the water level, the toggle is gradually operated until its joint 32 again passes the dead 30 center line whereupon the valves 7 and 17 are closed and the valve 6 opened with a quick action.

If desired, a cut out pipe 49 may be provided connecting the return pipe 43 and the 35 water outlet 45.

The body 1 is provided with a suitable blow out passage 50.

What I claim is:

1. In a steam trap, the combination of a 40 container having aligned inlet and outlet passages at its upper and lower ends, valves controlling said passages having stems extending toward each other, actuating means for the valves comprising an axially movable rod aligned and coacting with the stems, a support located in the container adjacent the rod, and means carried by the support and within the container for actuating the rod, said means comprising a float and mechanical connections between the float and the rod, substantially as and for the purpose described.

2. In a steam trap, the combination of a 45 container having aligned inlet and outlet passages at its upper and lower ends, valves for controlling the passages having stems, actuating means for the valves comprising an axially movable rod aligned and coacting

with the stems, toggle means having one of its links pivoted between its ends to the rod, 60 a spring connecting the toggle links, a float located in the container, a lever carrying the float, and connections between the lever and the other link of the toggle, substantially as and for the purpose specified. 65

3. A steam trap comprising a stationary container having inlet and outlet openings at its upper and lower ends, an equalizing passage at its upper end, valves for controlling the inlet, outlet, and said passage, 70 actuating means for the valves including an axially movable rod coacting with the inlet and outlet valves to open one valve and close the other, a lever pivoted within the container between its ends and having a float 75 on one arm thereof, a toggle, one link of which is pivoted between its ends to the rod, means connecting the other arm of the lever and the other link of the toggle, a spring connecting the toggle links and arranged to resist movement of the toggle links into a straight line to move the toggle to effect a quick action of the toggle when the joint thereof has passed the dead center line of the toggle, and springs tending to close 80 said valves, substantially as and for the purpose specified.

4. A steam trap comprising a stationary container having aligned inlet and outlet openings at its upper and lower ends, an equalizing passage at its upper end, valves for controlling the inlet, outlet, and said passage, actuating mechanism including an axially movable rod coacting with the aligned valves to open one valve and close the other, a lever 95 pivoted within the container between its ends and having a float on one arm, a toggle, one link of which is pivoted between its ends to the rod, means connecting the other arm of the lever and the other link of the toggle, a spring connecting the toggle links and arranged to resist movement of the toggle links into a dead center line to move the toggle to effect a quick action of the toggle when the joint thereof has passed the dead center line of the toggle, springs tending to close 100 said valves, and connections operated by the rod for opening the pressure equalizing valve, substantially as and for the purpose set forth. 105

In testimony whereof, I have hereunto signed my name, at Syracuse, in the county of Onondaga, and State of New York, this 17th day of Nov., 1916.

JOSEPH F. BRIGHTMAN.
